DESIGN FOR OPHTHALMIC WIRE

William A. Rohman, Attleboro, Mass.

Application November 21, 1946, Serial No. 134,976

Term of patent 14 years

(Cl. D57—1)

To all whom it may concern:

Be it known that I, William A. Rohman, a citizen of the United States and a resident of Attleboro, in the county of Bristol and State of Massachusetts, have invented a new, original, and ornamental Design for Ophthalmic Wire, of which the following is a specification, reference being had to the accompanying drawing, forming part thereof.

Figure 1 represents a top plan view of a length of wire, showing my new design, and

Figure 2 represents a cross section of Figure 1 on the line 2—2.

I claim:

The ornamental design for ophthalmic wire, as shown.

WILLIAM A. ROHMAN.
